UNITED STATES PATENT OFFICE

170,137

HAND CART

Phyllis M. Rogers, Port Credit, Ontario, Canada

Application September 19, 1952, Serial No. 21,528

Term of patent 3½ years

(Cl. D14—3)

To all whom it may concern:

Be it known that I, Phyllis M. Rogers, a subject of the Queen of Great Britain, and resident of the village of Port Credit, county of York, Province of Ontario, Canada, have invented a new, original, and ornamental Design for a Hand Cart, of which the following is a specification, reference being had to the accompanying drawing, forming part thereof.

In the drawing:

The figure is a perspective view of my new design for a hand cart.

The dominant features of my design reside in the portions shown in full lines.

I claim:

The ornamental design for a hand cart, as shown and described.

PHYLLIS M. ROGERS.
